Primary Examiner — Elizabeth Albert(74) *Attorney, Agent, or Firm* — Buchanan Ingersoll & Rooney PC(57) **CLAIM**

The ornamental design for an envelope for transport cover, as shown and described.

DESCRIPTION

The file of this patent contains at least one drawing/photograph executed in color. Copies of this patent with color drawings or photographs will be provided by the Office upon request and payment of the necessary fee.

Fig. 1.1 is a rear elevational view of an envelope for transport cover showing my new design in a closed configuration.

Fig. 1.2 is a front elevational view thereof.

Fig. 1.3 is a rear elevational view thereof, in an open configuration.

Fig. 1.4 is a right side elevational view thereof, in a partially open configuration.

Fig. 1.5 is a left side elevational view thereof, in a partially open configuration.

The broken lines representing perforations are included to show tear lines and do form a part of the claimed design.
